HANGER FOR SUPPORTING ARTICLES OF CLOTHING AND THE LIKE

John Irwin McClelland, Chicago, Ill., assignor to Universal Form Clamp Co., Chicago, Ill., a corporation of Illinois

Filed Dec. 17, 1962, Ser. No. 72,875

Term of patent 14 years

(Cl. D80—8)

FIGURE 1 is a perspective view of a hanger for supporting articles of clothing and the like embodying my new design;

I claim:

The ornamental design for a hanger for supporting articles of clothing and the like, substantially as shown.
